UNITED STATES PATENT OFFICE.

JAMES P. BOSHELL, OF COLDWATER, KANSAS.

DISCHARGE-FEED FOR UNLOADERS.

1,135,348.

Specification of Letters Patent. Patented Apr. 13, 1915.

Application filed August 7, 1912. Serial No. 713,873.

To all whom it may concern:

Be it known that I, JAMES P. BOSHELL, a citizen of the United States, residing at Coldwater, in the county of Comanche, 5 State of Kansas, have invented certain new and useful Improvements in Discharge-Feeds for Unloaders; and I do hereby declare the following to be a full, clear, and exact description of the invention, such as 10 will enable others skilled in the art to which it appertains to make and use the same.

This invention relates to discharge feeds for devices, such as manure spreaders and hay unloaders and has for its object the provision of novel means for simultaneously actuating the endless carrier and lower spreader cylinder of such devices, means being provided for regulating the speed of the endless carrier.

20 With the above object in view the invention consists of certain novel details of construction and combination of parts herein-after fully described and claimed, it being understood that various modifications may 25 be made in the minor details of construction within the scope of the appended claims.

In the accompanying drawings forming part of this specification:—Figure 1 is a 30 fragmentary side elevation showing the method of advancing the endless carrier one step.

Referring now to the drawings in which like characters of reference designate similar 35 parts, 10 designates an open bottomed box which is supported upon ground wheels 11 and 12. Secured to the box sides is a track upon which an endless carrier travels, the same comprising a plurality of slats 14 each 40 equipped at each end with two pairs of rollers 15 and 16 which engage the top and bottom faces of the track. The endless carrier is mounted on an idle roller 17 which is journaled at the front end of the box and 45 actuated by a driving roller which is journaled at the rear end of the box, sprocket chains being trained over gears carried by these rollers. The driving roller is equipped with a ratchet gear 21.

50 A rock lever 22 is journaled on the shaft of the driving roller and is equipped with a gravity pawl 23 which operatively engages the ratchet gear 21. The rock lever is held in position by a strap guide 24 secured to the 55 box. A reciprocating rod 25 actuates the rock lever through the instrumentality of a

pin 26 which works in a longitudinal slot 27 formed in the rock lever, means being provided as will be presently described for shifting the reciprocating rod vertically to 60 raise or lower the pin in the slot and thus advance the ratchet gear through a greater or smaller step than ordinary to vary the speed of the endless carrier.

The reciprocating rod 25 is carried in a 65 swivel bracket 28, and for rocking the rod on the bracket as a pivot a bell crank lever 29 is pivoted at the elbow to the box above the rod, one leg of the lever being loosely secured to the rod by a strap bearing 30, and 70 the other leg of the lever being connected by a rod 31 to an operating lever 32 which is pivoted at the lower end of the box near the front end thereof and is normally held stationary by a rack 33 secured to the box. By 75 disengaging the lever from the rack the lever may be shoved forwardly or rearwardly to rock the reciprocating rod on the swivel bracket and vary the position of the pin 26 in the slot 27 of the rock lever 22. 80

A fixed spur gear 34 is carried on each rear wheel 12. A vertically movable shaft 35 is mounted in suitable slots formed in the box sides and is supported by means of substantially horizontally disposed rocking 85 hanger rods 36 which extend rearwardly along the box sides and are pivotally secured at their rear ends as will presently be described. The shaft 35 is equipped at each end with a gear 37 adapted to mesh with 90 the related gear 34 when the shaft is at its lowest limit of movement with a resultant rotation of the shaft with the rear wheels 12. Above the shaft 35 a shaft 38 is journaled in the box sides and is equipped at each end 95 with a sprocket gear 39 over which and a related gear 40 on the shaft 35 a sprocket chain 41 is trained to connect both shafts for simultaneous rotation. A crank disk 42 is fixed to the shaft 38 and is equipped with 100 a pitman 43 which is pivotally connected to the reciprocating rod 25 and serves to actuate the latter.

In order to maintain the endless carrier quiescent when desired the shaft 35 is rocked 105 upward to disengage the gears 37 from the gears 34 and to attain this end a bell crank lever 44 is pivoted at its elbow on the box side, one leg of the bell crank lever being provided with an opening to loosely receive 110 the one end of the vertically movable shaft, and the other leg of the bell crank lever be-

ing connected by a rod 45 to an operating lever 46 which is pivoted to the box side and is normally held stationary by a rack 47.

A spiked cylinder 48 is journaled for rotation in the bracket arms 49 which project rearwardly from the box sides. The rear ends of the above mentioned hanger rods 36 are provided with openings to receive the ends of the cylinder shaft 50, the latter thus 10 forming a pivot upon which the rods rock in elevating the shaft 35 to disengage the clutch gears. Sprocket gears 51 are secured to the cylinder shaft and over these gears and similar gears 52 on the vertically movable shaft 35 sprocket chains 53 are trained to connect the spiked cylinder for simultaneous actuation with the endless carrier.

A leveling rake 54 is secured to the box sides above the spiked cylinder by bracket arms 55. All of the above described parts are utilized when it is desired to use the device simply as a manure spreader. However when the device is designed to be used for spreading a load of hay, straw or 25 the like over the field for fertilizing purposes the following additional parts are applied to the box. Side boards 56 are removably secured to the sides of the box through the instrumentality of pins 57 which are fixed to the side boards and are engaged in strap brackets 58 carried by the box sides. A pair of standards 59 are secured to the box sides in rear of the side boards and are provided at the upper ends with bearings 30 60 to removably secure the shaft 61 of a spiked cylinder 62 which projects slightly

above and in rear of the side boards. The cylinder shaft is equipped near the ends with sprocket gears 63 over which and similar gears 64 on the shaft 38 sprocket chains 40 65 are engaged. The spiked cylinder 62 is thus connected for simultaneous rotation with the endless carrier and spiked cylinder 45 48 and coacts with the latter named parts in spreading the load over the field.

What is claimed, is:—

The combination of a supporting wall, a bell crank lever pivoted on a horizontal pivot on said wall, and including a substantially vertically disposed leg and substantially horizontally disposed leg, a tubular bearing extending horizontally on said horizontal leg, a guide bearing pivoted on a horizontal pivot on said wall on one side of said bell crank lever, a ratchet lever disposed vertically on the opposite side of said bell crank lever and having a longitudinal slot therein, a horizontally disposed reciprocatory link engaged through said guide bearing and through said tubular bearing and 60 having a transverse terminal pin engaged through said slot, and a driving pitman connected to said rod in advance of said bearing, said bearing receiving the shocks incident to the change of direction of said pit- 65 man at each limit of its movement.

In testimony whereof, I affix my signature, in presence of two witnesses.

JAMES P. BOSHELL.
